UNITED STATES PATENT OFFICE.

WENDELL P. ANTHONY, OF RIDLEY PARK, PENNSYLVANIA, ASSIGNOR TO WILLIAM SIMPSON & SONS, OF PHILADELPHIA, PENNSYLVANIA, A FIRM COMPOSED OF WILLIAM P. SIMPSON.

TENTER-CHAIN.

1,242,121.

Specification of Letters Patent.

Patented Oct. 9, 1917.

Application filed July 13, 1915. Serial No. 39,641.

To all whom it may concern:

Be it known that I, WENDELL P. ANTHONY, a citizen of the United States, and resident of Ridley Park, Delaware county, 5 State of Pennsylvania, have invented certain new and useful Improvements in Tenter-Chains, of which the following is a specification.

This invention relates to tentering machines and more particularly to the chains which convey the cloth through the machine.

It has been the custom heretofore to make the chains up of a series of links which are 15 pivoted together and because of the great length of the chains the cost of manufacture has necessitated that the links be made of malleable iron and the cloth gripping surfaces of the links of brass plates secured to 20 the links. The object of having the brass plates is to avoid staining the cloth which would result from rust of the iron, if the cloth came in contact with an iron surface. The cost of links made entirely of brass would 25 be prohibitive and therefore for the purpose of economy the iron links have been generally adopted. There has also been a considerable amount of machine work necessary in finishing the links and this has made 30 them rather expensive even when made of iron.

It is the object of the present invention to provide a one-piece die-cast link which will be made of a composition suitable for the 35 purpose and will also eliminate the machine work which has been heretofore necessary in connection with the iron links.

A link embodying my invention is shown in the accompanying drawings, in which, 40 Figure 1 is a side elevation of the link; and

Fig. 2 is an end elevation thereof.

Referring to these drawings, 10 indicates the body of the link, which is provided with

an opening 11 and a single ear 12 at one end 45 and two ears 13 at the other end. The ears 12 are adapted to enter the space between the ears 13 on the next adjoining links and the links are fastened together by suitable pivot pins which extend through the openings 14 and 15 in the ears. From the upper side of the body 10 there projects a substantially horizontal ledge 16 having a slot 17 therein. The upper surface 18 of the ledge 16 is the cloth gripping surface with which 50 the gripper 19 co-operates. This gripper has the usual tail 20 and is connected with the spaced upwardly projecting arms 21 and 22 by a pivot pin 23. The arms 21 and 22 extend over the ledge 16, as clearly shown in 55 Fig. 2, and are integral with the body 10.

The link, as above described, is made by the die-casting process and all machining of the link is eliminated, the openings 14 and 15 and also the openings 24 for the pin 23 60 are formed in the casting in a manner well known to those skilled in the die-casting art.

A link made in accordance with my invention has all of the advantages of the ordinary form of link and can be produced at a 70 fraction of the cost of the latter. The improved link also has the advantage of being absolutely uniform throughout and all links made by the same dies are identical so that there will be no difficulty in assembling the 75 links.

Having described my invention what I claim and desire to secure by Letters-Patent is:—

A complete die-cast tenter chain link consisting of one piece only of non-rusting material and having a cloth-gripping surface and spaced upwardly projecting arms extending over said surface and provided with aligned openings for a gripper pivot. 80 85

In testimony whereof I affix my signature.

WENDELL P. ANTHONY.
